UNITED STATES PATENT OFFICE.

ROBERT AUGUST STEINERT, OF WASHBURN, WISCONSIN.

GUN. -

SPECIFICATION forming part of Letters Patent No. 487,586, dated December 6, 1892,

Application filed May 6, 1892. Serial No. 432,093. (No model.)

To all whom it may concern:

Be it known that I, ROBERT AUGUST STEINERT, of Washburn, in the county of Bayfield and State of Wisconsin, have invented a new and Improved Gun, of which the following is a full, clear, and exact description.

The object of the invention is to provide a new and improved gun which is simple and durable in construction, very effective in operation, and arranged to securely lock the cartridge in place for firing and at the same time actuate the firing-pin.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a side elevation of the improvement as applied. Fig. 2 is a plan view of the same. Fig. 3 is an enlarged transverse section of the same on the line 3 3 in Figs. 2 and 5. Fig. 4 is a similar view of the same on the line 4 4 in Fig. 6. Fig. 5 is an enlarged sectional side elevation of the improvement as applied with the breech-block in a lowermost position and the cartridge loader and extractor withdrawn, the section being taken on the line 5 5 in Fig. 7. Fig. 6 is a similar view of the same with the breech-block closed and the cartridge loader and extractor in an uppermost position, and Fig. 7 is a plan view of the improvement shown in Fig. 5.

In the breech A of the gun is formed a vertically-extending recess B, formed with guideways B', in which is fitted to slide vertically the breech-block C, formed on its top with a semicircular recess D for the reception of the cartridge E to be pushed into the bore of the barrel F. When the breech-block C is in a lowermost position and a cartridge is thrown into the open end of the recess B, the cartridge falls into the said semicircular recess D, as is plainly illustrated in Fig. 5, and is then in alignment with the bore of the barrel F.

From one side of the breech-block C extends outward a stud C', passing through a vertical

slot A', formed in one side of the breech A. (See Fig. 1.) The outer end of the stud C' engages a slot formed in the arm G' of a bell-crank lever G, fulcrumed on a stud G², secured in the side of the breech A. The other arm G³ of the bell-crank lever G extends upward and forms a handle to permit the operator to conveniently actuate the said bell-crank lever to raise and lower the breech-block C. When the bell-crank lever G is in the position shown in Fig. 1, the breech-block C rests in the bottom of the recess B in the breech A, and when the arm G³ of the said bell-crank lever is thrown rearward the breech-block C is caused to slide upward in the guideways B' in the recess B. The front end of the breech-block C then engages the flanged end of the cartridge, so as to lock the latter in place in the bore of the barrel F.

On the top of the breech A are arranged horizontally-extending guideways H, in which is fitted to slide a plate I, adapted to open and close the recess B at the upper end thereof. On the rear end of the plate I is formed a knob or handle I' for conveniently manipulating the said plate, and on the front end of the latter is arranged a stop I², adapted to abut against a stop-pin I³, secured on the breech A, near the rear end thereof, so as to limit the outward-sliding motion of the plate I. On the under side of the plate I and near the middle of the same is arranged a cartridge pushing and extracting device J, provided with a fixed arm J', extending downward and formed with a forwardly-extending lug J², adapted to engage the outer face of the flange of the cartridge, as will be readily understood by reference to Fig. 5. A second arm J³ is arranged in front of the arm J² and is held on the free end of a spring J⁴, attached to the under side of the plate I. On the lower end of the spring-supported arm J³ is formed an inclined foot or projection J⁵, adapted to engage with its back the inner edge of the flange of the cartridge opposite the lug or foot J². The inclined part of the foot J⁵ permits the arm J³ to move upward at the time the cartridge moves into proper position in the bore of the barrel F, so as to finally pass over the flange of the cartridge to engage the

same, as shown in Fig. 6. The fixed arm J' then engages the flange of the cartridge on one side and the spring-supported arm J³ engages the flange of the cartridge on the opposite side, the two arms then forming an extractor, and when the plate I is withdrawn the empty cartridge-shell is carried outward by the said two arms beyond the breech A to be dropped from the rear end thereof.

In the breech-block C is formed a recess or bearing for the firing-pin K, which is inclined, as shown, and arranged to engage with its front end the cartridge at the time the breech-block C is in an uppermost position. (See Fig. 6.)

In order to prevent the firing-pin K from turning in its bearing in the breech-block, a groove K' is cut longitudinally in the top of the said pin and is engaged by the lower end of the set-screw I, screwing in the breech-block C. On the under side of the firing-pin K are formed two recesses or notches K² and K³, of which the outermost notch K² is engaged by the free end of a spring N, secured to the under side of the breech-block, the said spring serving for projecting the pin, as hereinafter more fully described. When the breech-block is in a lowermost position, the front end of the firing-pin K rests against an inclined lug B², formed vertically in the recess B and in line with the bore of the barrel F. (See Figs. 5, 6, and 7.) When the breech-block C moves downward, the firing-pin K travels over the inclined lug B², whereby the firing-pin is pressed rearward and its spring N is compressed.

In order to unlock the firing-pin K for projection by the force of the spring N, the following device is provided: The catch K³ of the firing-pin is adapted to be engaged by a ridge O', formed on top of a lever O, extending transversely in the breech-block C and pivoted thereto at O², as will be readily understood by reference to Fig. 3. A spring O³, held in the breech-block, presses against the under side of the said lever O, so as to move the latter upward to engage the ridge O' with the notch K³. On the free end of the lever O rests a vertically-extending pin P, mounted to slide loosely in the breech-block C, the upper end of the said pin being adapted to be engaged by a lug Q, projecting from a slide Q', mounted to slide longitudinally in the top of the breech A at one side thereof. On the slide Q' is formed a laterally-projecting knob or handle Q² for conveniently moving the slide Q' forward or backward, so as to move the lug Q into or out of the path of the free end of the pin P. A spring Q³, pressing on the knob or handle Q², serves to lock the slide Q' in either a forward or backward position. Now when the slide Q' has been moved rearward then the lug Q is directly above the upper end of the pin P, and when the breech-block C is lifted, as before described, then the said pin P moves in contact with the lug Q,

is consequently pressed, and on account of resting on the lever O causes a downward swinging of the latter to move the ridge O' below the firing-pin K, so that the latter is free to slide in its bearing in the breech-block C to fire the cartridge in the usual manner. When the slide Q' is in a forward position, then the lug Q is out of the path of the pin P, and when the breech-block C is lifted then the ridge O' remains in the notch K³, thus locking the firing-pin K in place and preventing its outward sliding.

It is understood that when the lug Q presses the pin P, as above described, to free the firing-pin K to permit of firing the cartridge then on the downward motion of the breech-block C the firing-pin is moved into a rearmost position by traveling over the inclined lug B². As the breech-block C descends, the pin P moves away from the lug Q and the spring O³ causes an upward sliding motion of the lever O, so as to bring the ridge O' in contact with the under side of the firing-pin K. Now when the latter slides rearward by traveling down the inclined lug B² the ridge O' finally snaps into the notch K³ and holds the firing-pin in position. It is understood that the firing-pin remains in this locked position until the breech-block C is nearing its uppermost position, and the firing-pin is released by the lever O' swinging downward, this being caused by the pin P engaging the lug Q.

It is understood that the spring N is made sufficiently strong so as to push the firing-pin K forward with sufficient force to fire the cartridge.

The operation is as follows: When the breech-block C is in a lowermost position and the plate I is in a rearmost position, as shown in Fig. 5, then the operator places the cartridge E in the recess B so that the cartridge rests on the semicircular recess D in the top of the breech-block C. The operator then takes hold of the knob I' of the plate I and pushes the same forward, so that the loading and cartridge-extracting device J pushes on the rear end of the cartridge E, so that the latter slides off the breech-block into the bore of the barrel F. When the flange of the cartridge abuts against its recess in the end of the barrel, the operator moves the plate I still farther forward. Then the incline of the foot J³ of the spring-supported arm J³ slides over the flange of the cartridge and engages the same at the front edge opposite the lug J². (See Fig. 6.) The cartridge loading and extracting device is then in position to withdraw the empty shell after firing. After the cartridge is in place the operator pulls the arm G³ of the bell-crank lever G rearward, so as to raise the breech-block C in the recess B, and in doing so the front end of the breech-block passes against the end of the cartridge, and when the said breech-block nears its uppermost position the firing-pin K is released by the lever O sliding downward, as before ex-

plained, after which the spring N forces the firing-pin K forward, thus firing the cartridge. The operator then swings the arm G³ forward to lower the breech-block C, whereby the firing-pin K is again set by the ridge O' of the spring-pressed lever O engaging the notch K³. The spring N is at the same time compressed by the firing-pin K sliding rearward in passing down over the inclined lug B². When the breech-block C is in the lowermost position, the operator pulls on the knob I', so as to move the plate I rearward, whereby the cartridge loading and extracting device J withdraws the cartridge as the two arms J' and J³ engage the flange of the cartridge, as before described. The plate I is drawn rearward with a jerk, so that the stop I² in striking on the pin I³ gives sufficient jerk to the spring J⁴ so that the cartridge drops out between the lug J² and foot J⁵ of the arms J' and J³, respectively. A new cartridge is then placed in the open recess B and the above-described operation is repeated.

When it is desired not to fire but to load the cartridge into the barrel, then the slide Q' is moved forward, so as to move the lug Q out of the path of the pin P. When the breech-block is then raised, the firing-pin K is not unlocked, as the lever O is not depressed, and consequently the firing-pin K remains locked.

Having thus described my invention, I claim as new and desire to secure by Letters Patent—

1. The combination, with the breech having a transverse recess through it, of a sliding breech-block mounted in said recess, a spring-projected firing-pin mounted in the said block, a detent or sear to engage the firing-pin and hold it retracted, a cam or incline on the breech in the downward path of the firing-pin to retract it, and a releaser for the firing-pin to release its sear or detent when the breech-block reaches its inner or closed position and adapted, also, to be moved into an inactive position, substantially as set forth.

2. The combination, with a breech-block and its spring-projected firing-pin having a notch in its lower side, of a transverse spring-actuated lever or detent to snap into the notch when the firing-pin is retracted and a vertically-extending pin resting at its lower end on said lever or detent to disengage it from the notch when pressed downwardly, substantially as set forth.

3. The combination, with the breech and the sliding breech-block carrying the spring-projected firing-pin and its locking-lever or detent, of an incline on the breech in the path of the firing-pin when the block is moved downward to retract the said pin and a releasing mechanism for the said locking-lever or detent, substantially as set forth.

4. The combination, with the breech and the breech-block therein provided with a spring-projected firing-pin, a detent or lever to lock the pin when retracted, and a releas-

ing-pin, of a lug mounted movably on the breech and having a finger-piece for throwing it into and out of the path of the releasing-pin, substantially as set forth.

70

5. In a device of the class described, the combination, with a breech-block mounted to slide, of a spring-pressed firing-pin held in the said breech-block, a lever for locking the said firing-pin in position, a pin engaging the said lever and held with the latter in the said breech-block, and a lug held on the stock and adapted to engage the said pin at the time the breech-block slides in position for the firing-pin to engage the cartridge, substantially as shown and described.

75

6. In a device of the class described, the combination, with a breech-block mounted to slide, of a spring-pressed firing-pin fitted to slide in the said breech-block, a spring-pressed lever held in the said breech-block and adapted to engage the said firing-pin, and a fixed inclined lug adapted to engage the said firing-pin on the downward movement of the said breech-block to move the said firing-pin rearward in engagement with the said spring-pressed lever, substantially as shown and described.

80

7. In a device of the class described, a cartridge loader and extractor comprising a plate fitted to slide on the breech, a fixed arm on the said plate, and a spring-supported arm arranged in front of the said fixed arm, substantially as shown and described.

85

8. In a device of the class described, a cartridge loader and extractor comprising a plate fitted to slide on the breech, a fixed arm on the said plate, and a spring-supported arm arranged in front of the said fixed arm, the said spring-supported arm being provided at its foot with an inclined front edge to pass over the flange of the cartridge, substantially as shown and described.

90

9. The combination, with the breech having a recess open at its top and a portion of its rear end and a breech-block sliding vertically in the recess and having a cartridge-groove in its upper face, of a slide over the upper open end of said recess and provided with a depending arm to push the cartridge forward from the block into the barrel, substantially as set forth.

95

10. The combination, with the breech provided with a recess open at its upper end and rear and the vertically-sliding breech-block carrying the firing mechanism and provided with an operating-lever, of the slide closing the upper end of the recess and having a depending fixed arm to push the cartridge from the slide into the barrel and a spring-supported depending arm in advance of the fixed arm to snap over a cartridge-rim when the slide is pushed inwardly and extract the shell when the slide is slid rearwardly, the said breech-block abutting at its forward upper corner the rear edge of the said depending fixed arm, substantially as set forth.

100

11. The combination, with the breech provided with a recess open at its upper end and rear and the vertically-sliding breech-block carrying the firing mechanism and provided with an operating-lever, of the slide closing the upper end of the recess and having a depending fixed arm to push the cartridge from the slide into the barrel and a spring-supported depending arm in advance of the fixed arm to snap over a cartridge-rim when the slide is pushed inwardly and extract the shell when the slide is slid rearwardly, the said breech-block abutting at its forward upper corner the rear edge of the said depending fixed arm, substantially as set forth.

105

110

115

120

125

130

11. The combination, with the breech-block having a longitudinal bore and a recess through its lower side intersecting said bore, of the notched firing-pin sliding in the bore and the V-shaped spring, the forward upward projecting member of which extends up through the recess into the notch in the firing

pin and the rear member of the spring being removably secured to the lower side of the block, substantially as set forth.
